UNITED STATES PATENT OFFICE.

DANIEL J. PURDY, OF WHITE PLAINS, NEW YORK.

EXPANSIBLE BRUSH.

No. 817,837.

Specification of Letters Patent.

Patented April 10, 1906.

Application filed November 15, 1895. Serial No. 237,453.

To all whom it may concern:

Be it known that I, DANIEL J. PURDY, a citizen of the United States, residing at White Plains, in the county of Westchester 5 and State of New York, have invented certain new and useful Improvements in Expansible Brushes, of which the following is a specification.

My present invention pertains to an improved 10 expansible brush the construction and advantages of which will be hereinafter set forth, reference being had to the annexed drawings, wherein—

Figure 1 is a side elevation of the brush in 15 its normal collapsed condition; Fig. 2, a similar view showing the brush in its expanded position within a bottle, the latter being indicated in section; and Fig. 3, a perspective view of the brush in its expanded position.

The object of the present invention is to 20 provide a simple and effective expansible brush which when in its collapsed position may be readily passed into a bottle (or other container) to be cleaned and therein expanded, the brush-faces coming into working contact with the inner face of the side walls and bottom of the bottle.

In the drawings, A denotes the hollow spindle or supporting member provided at 25 its upper end with two diametrically vertically disposed slots B. An actuating stem or rod C extends downwardly into the upper end of the spindle, its lower end being supported by a block D, the block in turn resting upon a coiled spring E. The opposite end of the spring bears against a plug F, secured in the lower end of the spindle. Rod C has secured to it or formed integral therewith a collar G, provided with fingers or lugs H, the 30 collar being of such diameter as to make a neat fit with the inner face of the spindle. Lugs H project into the slots B, and thereby prevent the rod C from turning. They also 35 act as stops to arrest the inward movement of the rod coming into contact with the lower walls of the slots when the brush is fully expanded, as shown in Fig. 2.

Pivotal secured to one side of the upper or outer end of spindle or support A is a 40 brush or brush member I, the brush being of approximately the same length as the bottle to be washed or cleaned. To its outer end is pivoted a second brush member J, which may be termed the "bottom brush." The outer 45 end of the actuating-rod C is pivotally connected to said bottom brush at the mid-

length of the latter. The pivotal connection in the form shown is effected by slotting the brush - body and passing the reduced and slightly-curved end of the rod into the slot or 50 opening, where it is secured by a pin K.

A short brush or brush-section L is pivotally secured to that end of the bottom brush J opposite the long side brush I, the lower end of said section L in turn being pivotally 55 connected to a spreader or link M. Said link at its inner end is bifurcated and straddles rod C, to which it is pivotally connected. A second short side brush or brush-section N is pivotally connected at one end to the upper 60 end of the spindle A opposite the connection of the long side brush I. The upper end of brush N is pivotally connected to a link or spreader O, which in turn is pivotally connected to the rod in a manner similar to 65 link M.

Normally when the rod C is projected outwardly by spring E the parts occupy the positions shown in Fig. 1, the long side brush I lying close against the rod, with the bottom 70 brush tilted and brought into alignment with said side brush. By reason of the curvature given to the upper end of the rod and the slight curvature of the adjacent ends of brushes J and L the latter and its link or 75 spreader M will stand in approximate parallelism with the rod and in alignment with brush-section N and its spreader or link O. Links M and O and brush N lie close to the 80 rod, so that the brush as a whole presents a 85 minimum width when in a collapsed position, which permits it to be readily passed into a bottle - mouth and likewise obviates to a great extent the necessity for accurately positioning the bottle. This is a point of manifest advantage where the bottles are carried to the brushes in a holder or if a series of 90 brushes be moved into a series of bottles. When the collapsed brush is within the bottle and a relative movement of the brush and 95 bottle takes place, the uppermost end of the bottom brush J comes into contact with the bottom of the bottle and rocks or swings 100 down into a horizontal position. In so doing rod C is moved inward and the spring E 105 compressed. The long side brush I is swung outward and links or spreaders M and O are brought into substantial parallelism, whereby the short side brushes L and N are carried 110 into practical alignment and into contact with the bottle. So long as the brush and bottles are held against longitudinal move-

ment or separation the brush - faces will sweep over the entire interior surface of the bottle.

The brush-sections are held against twisting or torsional strains by the construction shown, the collar G and its lugs preventing twisting of the rod and the rod by reason of its passing into the bottom brush preventing said brush from twisting. Brush I being sustained at both ends has no tendency to twist, while the links M and O and the pivotal connection of the other ends of brushes L and N prevent said brushes from twisting.

Having thus described my invention, what I claim is—

1. In combination with a supporting member, a spring mounted therein; a rod extending into the supporting member, bearing upon the spring and normally protruded thereby; a bottom brush-section pivotally connected at substantially its mid-length to the outer end of the rod; a long side brush pivotally connected at one end to one end of said bottom brush and at its opposite end to the supporting member; a short brush pivotally connected to the opposite end of the bottom brush; a link connecting the other end of said short brush to the rod; a second short brush pivotally connected to the upper end of the supporting member; and a link connecting the outer end of said second short brush to the rod.

2. In combination with a supporting member; a rod; a spring for projecting said rod; a long side brush pivotally connected at one end to the supporting member; a short side brush pivotally connected to said member; a bottom brush pivotally connected to the end of the rod and to the upper end of the long brush; a second short side brush pivotally connected to the bottom brush; and means for throwing said short side brushes out into alignment with each other when the other brushes are brought into operative position.

45 3. In combination with a supporting mem-

ber; a spring-projected rod carried thereby; a brush pivoted at one end to said supporting member; and a second brush pivoted at substantially its mid-length to the outer end of the rod and likewise connected at one end to the outer end of the first-mentioned brush.

4. In combination with a supporting member; a spring-projected rod carried thereby, the outer end of said rod being curved to one side; a brush pivoted at one end to the supporting member; a second brush provided with an opening into which the curved end of the rod passes; a pivotal connection between said rod and brush; and a pivotal connection between the adjacent ends of the 60 brushes.

5. In combination with a hollow supporting member provided at its upper end with a pair of oppositely-disposed slots; a spring mounted in said member; a rod bearing at 65 one end on the spring; a collar carried by the rod and making a working fit with the inner face of the supporting member; fingers extending out from the collar into the slots in the supporting member; a relatively long 70 brush pivotally connected to said member; a brush pivotally connected at one end to the upper end of the first brush and likewise connected at its mid-length to the upper end of the rod; a short brush pivotally connected 75 to the other end of said second brush; a link pivotally connected to the opposite end of said short brush and the rod; a second short brush pivoted to the upper end of the supporting member; and a link pivotally connected to the upper end of said brush and the rod.

In testimony whereof I have signed my name to this specification in the presence of two subscribing witnesses.

DANIEL J. PURDY.
